METHOD FOR INSTALLING JOINTS IN
PLASTIC ROADS

John N. Heltzel, Warren, Ohio

Application January 26, 1943, Serial No. 473,640

8 Claims. (Cl. 94—22) •

The present invention relates to Methods for installing joints in plastic roads, and is a continuation-in-part of my co-pending application Serial No. 363,056, filed October 26, 1940, and entitled Combination road building machine and concrete spreader.

The invention has for its general aim and purpose the installing of expansion and contraction joints in concrete or other roadways while undergoing construction in plastic condition.

An object of the invention is to provide, either alone or in conjunction with a finishing machine and a supplemental subgrader, a device for carrying out the method of preparing the concrete to be routed out where transverse contraction or expansion joints are to be placed, in which the purpose of the device is to separate the plastic concrete from the earth and to avoid the casual or accidental mingling of any earth with the concrete in the process of routing or removing of the concrete preparatory to the placing of the joint.

The invention also has for a further object the use of certain improved steps and processes of a method whereby the subgrade is prepared, joint excavations made in the concrete and the finishing of the concrete accomplished by such steps as transverse and longitudinal spreading of the concrete, screeding, tamping, follow-up screeding and other finishing operations.

The invention has for a still further object an improved method by which a plate, or equivalent device, is originally laid on the subgrade, the plastic concrete poured thereover and finished to a degree; whereupon the concrete, while yet plastic, is shoveled or routed out in a transverse zone above, and defined by, the plate, and as soon as it is reached, the plate itself is lifted out and the expansion or contraction joint installed in the clean clear cut well defined space provided.

With the foregoing and other objects in view, the invention will be more fully described hereinafter, and will be more particularly pointed out in the claims appended hereto.

In the drawings, wherein like symbols refer to like or corresponding parts throughout the several views,

Figure 1 is a perspective view, with parts broken away and parts shown in section, illustrating a form of shoveling plate and method of installing expansion and contraction joint, as constructed and practiced according to the present invention.

Figure 2 is a transverse vertical section taken on the line 2—2 of Figure 1.

Figure 3 is a similar view taken on the line 3—3 of Figure 1.

Figure 4 is a fragmentary perspective view of an expansion joint employed.

Figure 5 is a similar view of a form of contraction joint employed.

Figure 6 is a perspective view showing a modified form of the invention.

Figure 7 is a side elevation of a machine for installing joints, shown above a roadway partly in section.

Figure 8 is a cross section through the roadway way with the machine shown in front elevation.

Figure 9 is a cross section taken on the line 9—9 in Figure 7.

Figure 10 is a perspective view of a form of container employed.

Figure 11 is a similar view showing a modified form of container, and

Figure 12 is a vertical section taken on an enlarged scale through one of the channels with a double dowel bar heavy load transfer device mounted therein.

Referring more particularly to Figures 1, 2 and 3, the subgrade is preferably prepared by dampening, by cutting, by dragging, by compacting, and above all by vibrating during all or any one of these various steps; the subgrade being thus treated and prepared between the customary side forms 16 upon which the finishing machine, bridge or other machine may roll and be supported for carrying out the subsequent operations of pouring the concrete, spreading the concrete, finishing, and practicing the steps of the improved method as hereinafter set forth.

The plastic concrete is shown generally at 68, and the various steps of preparing the subgrade, 40 pouring and finishing the concrete are more fully described in my co-pending application aforesaid.

In carrying out the improved method, there is placed on the subgrade, before the pouring of the concrete, a removable shoveling plate 88, of sheet metal or other suitable material; illustrated and described in my co-pending parent application heretofore referred to.

The shoveling plate 88 is positioned transversely 50 of the roadway in the line of a proposed expansion or contraction joint. The concrete is then poured over this shoveling plate, and over the subgrade generally, and is spread and surfaced. After the finishing machine has roughly surfaced 55 the plastic mass, the shoveling plate will be in

position on the bottom of the subgrade, as indicated at 88—A in Figure 1. In other words the shoveling plate will be covered by the superimposed mass of concrete forming part of the continuous roadway.

While the concrete is still plastic, the plastic mass directly above the plate is shoveled or removed from the plate 88 and thrown up on each side of the plate which act will expose the shoveling plate, as indicated at 88—B in Figure 1, at which time the shoveling plate may be lifted out of position. For this purpose the plate 88 has upstanding end flanges 89, which are bowed up centrally and provided with perforations 90 to receive the fingers, a hook or suitable tool for pulling the plate out of the concrete. The flanges 89 and the upwardly bowed portions thereof serve to elevate the openings 90 to a position where it is convenient to grasp the same.

When the plate 88 is removed it will expose the subgrade of the roadway, as indicated at 88—C, and the plate will have facilitated this operation, at the same time making it impossible to shovel clay, earth or other foreign matter from the subgrade to become undesirably mixed with the concrete.

An expansion joint or contraction joint is then placed on the subgrade, as indicated at 88—D in Figure 1, and the concrete is shoveled against the expansion joint and is spaded and tamped around the expansion joint or contraction joint, which may be of any conventional type, particularly that type of expansion joint in which is utilized short dowel bars with load transferring devices. Such joints are indicated in Figures 4 and 5.

Figure 4 shows an expansion joint which may be used and Figure 5 shows a desirable type of contraction joint. Both of these types of joint, which will be understood by those skilled in the art, require a very narrow channel across the roadway in which to deposit the expansion joint usually not more than ten inches being required.

In Figure 4, 91 designates the plate or strip of an expansion joint, 92 is short dowel bars and 93 the load transferring devices.

In Figure 5 the contraction joint strip or plate 94 is shown as associated with the short dowel bars 95 and with the load transferring devices 96.

It will be appreciated by those versed in the art that heretofore expansion and contraction joints were staked or otherwise secured to the subgrade prior to the placing of the concrete. During the finishing operations, that is due to the thrust of the finishing machine together with the surge of the mass of concrete against the expansion or contraction joints, the joints were often forced out of alignment. In addition, the dowel bars were often forced out of parallel position, which has been found to be detrimental. The present method of placing the joints speeds the pouring of the concrete because of the placing of the joints back of the pouring and finishing operations. It has been found desirable to vibrate the concrete locally about the joints to insure perfect amalgamation and compaction of the concrete.

The flanges 89 may engage against the side forms 16, as shown in Figures 2 and 3, to assist in maintaining alignment of the shoveling plates 88 against movement.

Referring more particularly to Figure 6, therein is shown another method of producing the channel 88—C in the concrete by placing a series of containers 20 on the subgrade 21. These con-

ainers are in a series transversely across the roadway from side form 16 to the opposite side form 16. Some of these containers are longer and deeper than others to form lateral depressions in the subgrade at a depth below the common elevation of the subgrade; these depressions when filled with concrete form brackets or reinforcing elements to prevent slab curling, also to accommodate heavy load transfer devices to be installed. In depth the containers may be equivalent to the depth of the roadway, or a layer thereof, which it is desired to build.

The containers may be submerged by the concrete as shown at 20—A. Immediately after the concrete has been spread and surfaced, the first

15 time over, the boxes or containers 20 are lifted out of position, leaving the channel 88—C. The containers are filled with the plastic material of the roadway when the road material is poured.

20 When the containers are lifted out of place, the road material contained therein may be deposited immediately on top of the surfaced concrete along the channel 88—C, or if desired, the containers filled with the concrete may be placed aside to be

25 dumped in the channel 88—C later. At 22 mounds are shown at opposite sides of the channel 88—C to indicate that the plastic material from the withdrawn containers 20 has been deposited on the road surface.

30 After the containers 20 are removed from the road to produce the channel 88—C, dowel bars 92 together with a joint strip 91, are positioned on the subgrade and secured to alinement and held in position by an alining bar 23, which is

35 secured to the side forms 16 by cams or suitable clamping arrangement 24. The concrete is then thoroughly compacted and solidified or vibrated around the dowel bars and the joint by electrical or mechanical vibrators 23—A and the concrete thereupon receives its final surfacing treatment, as indicated at 25. After the compacting, surfacing and vibrating have been completed, the expansion joint, together with the dowel bars, are left installed as indicated at 25;

40 it being understood that after the alining bar 23 has served its purpose, it is withdrawn and removed to a new point of operation for repeated use.

45 Referring more particularly to Figures 7, 8, 9 and 10, a machine and method are disclosed for expediting the operation of joint installation, in which a corrugated receptacle 26, as shown in Figure 10, or in the modified form in Figure 11, to replace the shoveling plate 88 of Figure 1 or 50 the series of containers 20 of Figure 6.

55 The corrugated receptacle 26 is made of a length to extend all the way across the roadway between the side forms 16. This single receptacle 26 or 26—A is placed upon the subgrade, as indicated at 26—B in Figure 7. The concrete 27 is then poured between the side forms and into the receptacle and thereafter surfaced over the roadway by a machine moving in the direction of the arrow. This machine follows the pouring and spreading operation and it comprises a traveling bridge or carriage 28 having wheels 29 rolling along the side forms 16.

60 On the bridge 28 is an elevated framework 30 for supporting hoisting tackle of any kind, for instance consisting of a drum 31, an appropriate number of chains 32 wound thereon and a lever 33, ratchet 34 and pawl 35 arrangement connected to the drum 31 for rotating the same. Hooks 36 carried by the chains 32 are adapted 65 to engage end and side holes or perforations 37

and 38 in the receptacle 26 or 26-A. In this way the receptacles full of concrete, may be bodily lifted out of position as submerged in the concrete 27 in order to leave a channel in which the dowel bars 92 and joint strip 91 are subsequently positioned.

While secured in such position on the subgrade, concrete is dumped from the suspended receptacle 26 over the dowel bars and expansion strip and into the channel, thus replacing the plastic material over the joint strip and dowel bars. Platforms 39 on the bridge 28 are provided for workmen to manipulate the lifting apparatus and to dump the receptacle. After dumping the receptacle is released from the hooks 36 for re-use in a repeating operation.

The machine is now moved forward by hand or under its own power until the vibrating apparatus is positioned over the joint material over the channel containing the joint material as indicated at the left end of Figure 7. The vibrating apparatus comprises the vibrators 40, the strip or plate 41 and the forks or projections 42. The plate 41 forms a convenient medium to support the vibrators 40 and to carry the projections 42. The plate is supported by screw shafts 43, swivelly connected at their lower ends with the plate 41 and threadedly engaged through nuts 44 carried in any suitable manner by the carriage or bridge 28.

By turning down the screws 43, the forks or projections 42 will be made to penetrate the concrete which has been redeposited by the upturned receptacle into the channel containing the dowel bars and joint strip. Such projections 42 will carry the vibratory action of the vibrators 40 into the concrete body to cause reuniting of the concrete particles and the kneading of the material so as to produce a dense homogeneous structure in which the redeposited concrete will become one with the body of the road.

The zig-zag walls of the receptacles 26 or 26-A, produced by the corrugations, will avoid the possibility of developing planes of weakness adjacent the joint strip 91. The vibrating apparatus is arranged for vertical adjustment, for instance by the use of hand wheels 45. Electric power is provided by the power plant 46 mounted upon the carriage 28 and connected by a chain 47 and sprockets 48 and 49 with the wheels 29 or their axles. In this way the power plant 46 may drive the carriage 28, and at the same time through electrical cables 50 supply the necessary current to the vibrators 40. Dummy joints 51, or other part depth joints may be installed by a similar method, or may be vibrated into position as disclosed in my prior patents already issued. Final surfacing of the concrete is done in a conventional way, thus speeding production.

Referring back to Figure 7, the receptacles may be submerged into the subgrade so as to produce a transverse channel of a depth greater than the common subgrade elevation and also to form ribs in the walls of depression by the corrugations on the side walls of the receptacles as previously described in Figures 10 and 11. These formations or corrugations in the receptacles will form gussets or brackets, which serve as reinforcing elements along both sides of the abutting slabs to reinforce the slabs to prevent fractures of the concrete transversely along or close to the joint when great pressure is exerted due to expansion of opposing slabs; also these thickened edges along the transverse joints will permit the installation of heavier

load transfer devices and will also prevent slab curling.

It is obvious that various changes and modifications may be made in the details of construction and design of the above specifically described embodiment of this invention without departing from the spirit thereof, such changes and modifications being restricted only by the scope of the following claims.

10. What is claimed is:

1. The method of building concrete roads which consists in pouring and surfacing concrete over a plate, removing the concrete from over the plate, removing the plate to produce a channel, positioning an expansion joint and dowel bars to alignment within the channel, replacing the concrete, and compacting and finishing the concrete over the expansion joint and dowels.

2. The herein described method for building, and installing joints in, plastic roads which consists in dampening the subgrade, removing earth and other material from the dampened subgrade between the side forms down to a desired level, compacting the subgrade and vibrating the same, laying plates on the subgrade in positions to be occupied by the transverse joints, pouring and surfacing plastic concrete over said plates and subgrade, removing the concrete from above the plates and lifting out the plates, installing joints in the channels lately occupied by the plates, returning concrete in and about the joints and compacting and vibrating the same.

3. The herein described method of building, and installing joints in, roads formed of plastic material, which comprises insulating the plastic road material from the earth of the subgrades along predetermined strips, removing the plastic material from these predetermined strips without admixture of subgrade material, placing the joints in the channels formed by removal of the concrete, returning plastic material to the channels in and about the joints, and compacting and finishing the returned plastic material.

4. The herein described method for building, and installing joints in, roads formed of plastic material, consisting in placing side by side in a series across the roadway a number of containers, pouring plastic material on the subgrade and over said containers, removing the containers to produce a transverse channel, placing joint material in the channel, re-depositing plastic material in the channel and about the joint material, and surfacing and finishing the roadway above such re-deposited plastic and joint material.

5. The herein described method of preparing plastic roads under construction for joint material, consisting in initially placing on the subgrade a receptacle extending substantially across the roadway, pouring the plastic material in the normal manner on the subgrade and over and into such receptacle, raising the receptacle to produce a channel in the plastic material roadway for the reception of joint material, placing joint material in the channel and dumping the receptacle to re-deposit the withdrawn material into the channel in and about the joint material.

6. The method as herein described and claimed in claim 5, further consisting in vibrating the redeposited material in the channel in and about the joint material.

7. The method of forming subgrade and installing joints in concrete roads, comprising excavating of subgrade, placing in such excavations removable forming elements to mold formations in the subgrade, removing said elements,

placing joints and load transfer elements in the formations and pouring concrete on the subgrade and into such formations, thereby forming reinforcing elements integral with the body of the mass of concrete to reinforce the concrete structure adjacent to such joints and load transfer elements installed therein.

8. The method of installing joints in plastic material of a road under construction comprising positioning containers on the sub-base along the line of proposed joint, then pouring and spread-

ing the plastic material on the sub-base and in the containers, then removing the containers and the material therein and positioning joint material and instrumentalities, including load transfer devices on the subgrade along the line of joint, then returning the plastic material to submerge the joint and said instrumentalities, then vibrating, compacting and finishing the material over said joint and instrumentalities.

JOHN N. HELTZEL.
